J. A. LEWIN AND G. P. BARTLETT,
DISINFECTING MEANS OR ATTACHMENT FOR THE FLUSHING ARRANGEMENTS OF
WATER CLOSETS, URINALS, SINKS, AND THE LIKE.
APPLICATION FILED JUNE 28, 1919.

UNITED STATES PATENT OFFICE.

JOSHUA AARON LEWIN AND GEORGE PILCHER BARTLETT, OF DURBAN, SOUTH AFRICA.

DISINFECTING MEANS OR ATTACHMENT FOR THE FLUSHING ARRANGEMENTS OF WATER-CLOSETS, URINALS, SINKS, AND THE LIKE.

1,355,155.

Specification of Letters Patent. Patented Oct. 12, 1920.

Application filed June 28, 1919. Serial No. 307,457.

To all whom it may concern:

Be it known that we, JOSHUA AARON LEWIN, a subject of the King of Great Britain, and GEORGE PILCHER BARTLETT, a subject of the King of Great Britain, both residents of Durban, Natal Province, Union of South Africa, have invented certain new and useful Improvements in Disinfecting Means or Attachments for the Flushing Arrangements of Water-Closets, Urinals, Sinks, and the like, of which the following is a specification.

This invention relates to disinfecting means or attachments for the flushing arrangements of water closets, urinals, sinks and other conveniences, receptacles, appliances or contrivances which are cleaned or flushed out by a usually regulated supply of water.

Such flushing arrangements are commonly operated by means of a pull which, through the medium of a lever, operates the means controlling the discharge of the water from the cistern or tank to the closet, urinal, sink, etcetera.

The object of the present invention is to provide a disinfecting means or attachment which will be actuated by the said flushing stream in its passage from the cistern to the closet pan, etcetera. The disinfecting arrangement is such that upon the operation or movement of the pull or its equivalent a suitable quantity of the disinfectant is mixed with a suitable quantity of the flushing water and the mixture then flows down the flushing or "wash down" pipe to the point of discharge in the closet, etcetera. The arrangement is so designed that a quantity of the disinfecting mixture passes through the pipe to the closet after the main flushing stream has passed therethrough.

The apparatus or arrangement in its preferable form includes a pivoted member which on the one side enters the flushing or "wash down" pipe and on the other side enters a chamber or compartment in which the disinfectant is mixed with the water. The one end of this member is shaped so that when it is depressed by the flushing water flowing down the pipe it diverts a quantity of said main flushing stream into the mixing chamber. The other end of the device operates a valve or valve device which admits a quantity of the disinfectant to such chamber or compartment to mix

with the water. A small passage or conduit leads from the bottom of the mixing chamber to the "wash down" pipe through which the mixture flows. This construction insures that all the disinfecting mixture does not leave the mixing chamber until after the main flushing stream has passed down the pipe, so that a quantity is delivered after the passage of said main flushing stream and serves for disinfecting the water which remains in the closet pan, etcetera, until the flushing arrangement is again operated.

The invention will be more fully described with the aid of the accompanying drawings wherein—

Figure 1 is a perspective view partly in section of the disinfecting means or attachment applied to the flushing arrangement of a water closet, and showing the parts in the operative position.

Fig. 2 is a similar view also partly in section of certain parts of the arrangement in the other and inoperative position.

In the drawing A represents the cistern of an ordinary flushing arrangement for a water closet. B the "wash down" or flushing pipe down which the main flushing stream flows from the cistern A to the pan C of the closet. a is the pull for operating the means which control the discharge of the water from the cistern A in any ordinary or convenient manner. The disinfecting means or attachment comprises a vessel or container A¹ which is made of the requisite size or capacity and may be made of metal or any other suitable material. In the particular construction illustrated the vessel A¹ is divided into two chambers or compartments a¹, a² by the plate a³ which may be secured in position in any suitable manner. The upper chamber or compartment a¹ is utilized as the holder or container for the disinfecting material and the lower chamber or compartment a² is used as the chamber or compartment in which the disinfecting material is mixed with the water and from which the mixture is delivered to the "wash down" pipe B, as hereinafter explained.

The vessel A¹ may be constructed in one piece with or be suitably attached to a bracket or part a⁴ which serves for fixing it, by means of bolts a⁵ or other suitable means, to a further bracket or part a⁶ which is secured to the pipe B in a convenient position. The parts a⁴, and a⁶, may be con-

structed in one piece if preferred and be clamped, bolted or otherwise suitably connected to the "wash down" pipe on the one side and to the vessel A¹ on the other. A 5 hole or passage b is formed in the side of the vessel A¹ and extends through the bracket or brackets a⁴, a⁶ and through the pipe B so that the lower chamber or compartment a² is thereby placed in communication 10 with the interior of the pipe B.

In the passage b there is pivoted the lever or member C¹ whose one arm c¹ projects into the pipe B and whose other arm c² projects into the chamber a². That end of the arm c¹ which is in the pipe B is preferably hollowed or made of spoon-shape on the top. The arm c² which projects into the chamber a² is adapted to engage with and operate a valve or valve device D. In Fig. 1, 15 the arm c² is shown lifting and opening the valve D and in Fig. 2 it is shown in disengagement with the valve, which then assumes its closed position. This end of the lever C¹ is weighted or heavier than the 20 arm c¹ so as to maintain the lever or member C¹ in its normally inoperative position—see Fig. 1—with the valve closed.

The valve D is shown in the form of a 25 plug or coned valve and the plate a³ is shown constructed to provide a correspondingly shaped seating d. d¹ is a guide for the valve. The stem d² of the valve is engaged by the arm c² of the lever when the latter is operated, and the valve D thereby 30 raised and opened—see Fig. 1.

E represents the small port, passage or conduit leading from a point at or near the bottom of the chamber a² to the pipe B, through which the mixture of disinfectant 35 and water flows from the chamber a² into the pipe B.

The vessel A¹ is provided with a detachable or removable lid or cover a⁷ or other suitable means, for replenishing the disinfectant as required.

In the operation of the embodiment of 40 our invention illustrated in the drawings, the pull a is drawn down to discharge the water from the cistern A, down the "wash down" pipe B to the pan C. The flushing stream in its passage down the pipe B strikes the arm c¹ of the lever C¹ and moves the latter upon the pivot and causes it to assume the position in which it is shown in 45 Fig. 1. The inner arm c² lifts and opens the valve D whereupon a quantity of the disinfectant falls from the upper chamber a¹ into the mixing chamber a². Simultaneously the spoon-shaped end of the lever C¹ 50 diverts a quantity of the water from the pipe D through the hole or passage b into the mixing chamber where it mixes with the disinfectant. The mixture of water and disinfectant now runs out of the mixing 55 chamber a² through the small passage or

conduit E into the pipe B. The small passage E retards the flow of the mixture from the chamber a² so that it takes longer for the chamber a² to be emptied than for the main flushing stream to flow down the pipe B, consequently a quantity of the disinfecting mixture continues to flow down the pipe B and into the pan C, after the main flushing stream has ceased. This, as previously explained, insures the disinfecting of the 75 water which remains in the pan C until the flushing arrangement is again operated.

What we claim as our invention and desire to protect by Letters Patent is:—

1. Disinfecting means for the flushing arrangement of water closets, urinals, sinks and the like, comprising a container for the disinfectant, a mixing chamber, a valve device for permitting a quantity of disinfectant to pass from the container to the mixing 80 chamber, means for operating said valve which means comprise a pivoted lever the one end of which projects into the "wash down" or flushing pipe and is depressed by the main flushing stream and the other end of which contacts with and operates the valve, the end of the lever which projects into the "wash down" or flushing pipe also serving to deflect a quantity of the water 85 into the mixing chamber, an inlet near the top of the mixing chamber through which the quantity of water deflected by the lever is admitted into the mixing chamber and an outlet from the mixing chamber at the bottom thereof for the mixture to pass out into 90 the "wash down" pipe.

2. Disinfecting means for the flushing arrangements of water closets, urinals, sinks and the like, comprising a container for the disinfectant, a mixing chamber, a valve device for permitting a quantity of disinfectant to pass from the container to the mixing 105 chamber, means for operating said valve which means comprise a pivoted lever the one end of which projects into the "wash down" or flushing pipe and is depressed by the main flushing stream and the other end of which contacts with and operates the valve, the end of the lever which projects into the "wash down" or flushing pipe also 110 serving to deflect a quantity of the water into the mixing chamber, an inlet near the top of the mixing chamber through which the quantity of water deflected by the lever is admitted into the mixing chamber and an outlet from the mixing chamber at the bottom thereof for the mixture to pass out into 115 the "wash down" pipe, said outlet being such that it insures that a quantity of the disinfecting mixture will flow into the pan 120 through the "wash down" pipe, both during the operation of flushing and after said operation has ceased as set forth.

3. Disinfecting means for the flushing arrangements of water closets, urinals, sinks 125

and the like, comprising a vessel including a container and a mixing chamber and a diaphragm between said container and mixing chamber, which diaphragm is constructed to provide a valve seat, a valve seated in said diaphragm, for permitting a quantity of disinfectant to pass from the container to the mixing chamber, means for operating said valve, which means comprise 5 a lever pivoted between the vessel and the "wash down" or flushing pipe, the one end of which projects into the "wash down" or flushing pipe and is depressed by the main flushing stream, and the other end of which 10 contacts with and operates the valve, the end of the lever which projects into the "wash down" or flushing pipe also serving to

deflect a quantity of the water into the mixing chamber, an inlet near the top of the mixing chamber through which the quantity 20 of water deflected by the lever is admitted into the mixing chamber and an outlet from the mixing chamber at the bottom thereof for the mixture to pass out into the "wash down" pipe. 25

In testimony whereof we have signed our names to this specification in the presence of two subscribing witnesses.
